UNITED STATES PATENT OFFICE.

WALTHER AKEMANN, OF ESSEN, GERMANY, ASSIGNOR TO FRIED. KRUPP AKTIEN-GESELLSCHAFT, OF ESSEN-ON-THE-RUHR, GERMANY.

APPARATUS FOR THE ELECTRICAL LONG-DISTANCE CONTROL OF THE VALVE-GEAR OF A HYDRAULIC GUN-POINTING MECHANISM.

1,371,136.

Specification of Letters Patent.

Patented Mar. 8, 1921.

Application filed September 3, 1920. Serial No. 408,075.

To all whom it may concern:

Be it known that I, WALTHER AKEMANN, residing at Essen, Germany, a citizen of the German Republic, have invented a certain new and useful Improvement in Apparatus for the Electrical Long-Distance Control of the Valve-Gear of a Hydraulic Gun-Pointing Mechanism, of which the following is a specification.

10 This invention relates to such an apparatus for the electrical distance control of the valve gear of a hydraulic gun pointing mechanism which first enables the gun barrel to be adjusted in a manner which is specially 15 accurate and free from shock and secondly differs from other apparatus for the electrical long distance control of the valve gear of a hydraulic gun pointing mechanism by the fact that its valve gear takes up a considerably less amount of space. A similar structure is illustrated and described in my co-pending application, Serial No. 408,070.

The invention will be described with reference to the accompanying drawing which 25 shows a construction of an apparatus for the electric long distance control of the valve gear of a hydraulic gun pointing mechanism as applied to the elevating gear.

Figure 1 is a diagrammatic view, partially 30 in section, of the construction,

Fig. 2 is a horizontal section through a detail drawn to a larger scale, and

Fig. 3 is a section on the line 3—3 of Fig. 2, looking in the direction of the arrow x.

35 A denotes the barrel of a naval gun mounted on trunnions a². In order that the elevation can be imparted to the gun barrel A it is pivotally connected to the piston a⁴ of a double acting hydraulic cylinder A³ 40 pivotally mounted by means of two pins a⁵. The cylinder A³ is connected by pipes a⁶ and a⁷ with the casing of a controlling valve B arranged for long distance control. To the casing of the controlling valve B are also 45 connected a pipe b¹ for water under pressure and a pipe b² for carrying water away.

In the casing of the controlling valve B are provided two passages b³ and b⁴ for the admission of the water under pressure. The 50 movable part of the controlling valve B is formed by a piston rod C which terminates at its upper end in a rack c¹ and at its opposite end carries three controlling pistons c²,

c³ and c⁴ and the said controlling pistons are provided with valve sleeves. Into the rack c¹ 55 gears a toothed sector d¹ forming part of a gearing contained in a casing E, shown in Figs. 2 and 3, and will be more fully described hereinafter. The aforesaid gearing is for the purpose of making the movements 60 of the piston rod C of the controlling valve dependent on the one hand on the receiving motor F and on the other hand on the gun barrel A.

From the pipe b¹ for the water under pressure branch off two other pipes b⁵ and b⁶, which open into the pipes a⁸ and a⁹ leading to the cylinder A³. Two pipes a⁸ and a⁹ for carrying away water are also connected to the pipes a⁶ and a⁷. In the pipes b⁵ and a⁹ on the one hand and b⁶ and a⁸ on the other hand are placed two quick-acting cut-off devices G and H constructed in the form of valves and which can simultaneously open or shut off each of the pipes b⁵, a⁹ and b⁶, a⁸ connected to them.

The valve rods g¹ and h¹ of the cut-off devices G and H are each provided with two piston valves g², g³ and h², h³, which are held in the closed position by means of springs g⁴ 80 and h⁴ and can be drawn into the open position against the pressure of these springs by magnet cores g⁵ and h⁵ rigidly connected to the valve rods g¹ and h¹ and electrically excitable windings g⁶ and h⁶. The arrangement described therefore enables a series of pipes b¹, b⁵, a⁸ for water under pressure to be simultaneously opened or shut off by the operation of the cut-off device G and also a series of pipes a⁷, a⁹ for carrying water away 85 and a series of pipes b¹, b⁶, a⁷ for water under pressure and a series of pipes a⁸, a⁹ for carrying water away to be also simultaneously opened or closed by the operation of the cut-off device H.

The excitation of the magnet windings g⁶ and h⁶ is effected by a circuit closing device b⁷, c⁵, b⁸, which has a movable circuit closing device c⁵ and two fixed circuit closing devices b⁷ and b⁸. The movable circuit closing device is constructed as a rubbing brush and is so attached to the piston rod C of the controlling valve B that when the piston rod moves in one direction or the other it can come into contact with either the one or the other of the two circuit closing devices b⁷ 100 and b⁸.

105

and b^8 rigidly fixed with respect to the casing of the controlling valve B.

The movable circuit closing device c^5 is connected by a flexible conductor i^1 to the 5 positive pole of a continuous current main J. The fixed circuit closing devices b^7 and b^8 are connected by conductors g^7 and h^7 with each of the ends of the magnet windings g^6 and h^6 , the other ends being connected up in parallel and by a common return conductor i^2 to the negative pole of the continuous current main J.

The above mentioned long distance control apparatus contains a transmitter K 15 mounted at the observing station (see Fig. 1) which is constructed in the usual way so that the continuous current supplied to it by conductors (not shown) is converted into three dephased currents of variable strength. 20 These three dephased currents of variable strength are conveyed by a three-phase long distance conductor k^1 to the receiver F which is constructed as a synchronous motor, the said conductor k^1 being excited from the 25 continuous current main J. The transmitter K is adjusted by a milled head k^2 and a hand wheel k^3 , each of which is positively connected to a middle wheel k^4 and k^5 of a gun planet gear in the manner shown in

30 Fig. 1. The planet wheel k^6 of the gear is mounted on a bent down arm of the transmitter shaft k^7 . The adjusting apparatus which is rotated by the milled head k^2 is provided with an indicating device k^8 k^9 35 which indicates the adjusted range of the target and is used when the transmitter K is to have a rotation imparted to it which corresponds to the range of the target. The adjusting apparatus rotated by the hand wheel k^3 is positively connected to a telescope k^{10} which oscillates about a horizontal axis and is used when it is desired to eliminate the influence of an oblique position of the ship (e. g. when rolling or pitching) on 40 the elevation imparted to the gun barrel with respect to a horizontal plane.

The gearing which is intended to connect the piston rod C of the controlling valve to the receiving motor F and the gun barrel A 45 and substantially inclosed by the casing E is shown in Figs. 2 and 3. It contains two worm gears e^1 , e^2 and e^3 , e^4 mounted in the casing E and of which the one e^1 , e^2 is positively connected through a gearing e^5 f^2 50 with the shaft f^1 of the receiver F (see also Fig. 1) and the other through a gearing e^6 , e^7 , a^{10} , a^{11} , a^{12} , a^{13} (see Fig. 1) with the elevating sector a^{14} of the gun barrel A.

The two worm gears are connected by a 60 sun and planet gear e^8 , e^9 , e^{10} with an apparatus which regulates the stroke of the piston rod C of the controlling valve B and which is hereinafter termed the stroke apparatus. This stroke apparatus contains a 65 drum e^{12} which rotates with its shaft e^{11} in

the casing E and the axis of rotation of which coincides with the common axis of rotation of the worm wheels e^2 and e^4 and is provided on its outside with a rib e^{13} in the form of a helix. This rib e^{13} has on the 70 part which extends over the one half of the length of the drum a greater external diameter than on the part which extends over the other half. The transition from the one diameter to the other is formed by a transition arc e^{14} , which extends over only a comparatively short part of the rib e^{13} .

Against the rib e^{13} lies a roller d^2 which embraces it laterally and which is movable longitudinally on a bolt d^3 running parallel 80 with the axis of rotation of the drum e^{12} . The bolt d^3 is fixed to one forked lever arm D of a double-armed lever which is pivotally mounted on the casing E about an axis which is likewise parallel with the axis of 85 rotation of the drum and the other lever arm D⁴ thereof carries, on the part which protrudes from the casing, the toothed sector d^1 already mentioned which cooperates with the toothed rack c^1 of the piston rod C. 90 The lever arm D⁴ is under the action of a tension spring d^5 , which tends to rock the lever D D⁴ in such a way that the roller d^2 bears with pressure against the rib e^{13} .

In order to thoroughly understand the 95 working of the apparatus above described in the following description it will be assumed that the gun barrel has already been elevated to an amount which corresponds to a certain range adjusted on the transmitter K 100 and that the controlling valve B is in its central position. The movable circuit closing device c^5 is consequently also in its central position between the fixed circuit closing devices b^7 and b^8 , so that the circuits leading to the quick-acting cut-off devices G and H are broken and the cut-off devices themselves assume under the action of their springs g^4 and h^4 the closed position shown in Fig. 1. It will be also assumed that the 110 ship is in the central floating position and does not roll.

If now the gun barrel A is to have an elevation imparted to it which is different from the previous one, the milled head k^2 115 is rotated until the desired new range is adjusted on the indicating device k^8 , k^9 . When this is done the armature of the transmitter K is rotated with the milled head k^2 through the gearing k^4 , k^6 , k^7 and the armature of the receiver F which is connected to the receiver K by the long distance conductor k^1 assumes a corresponding position. The shaft f^1 and with it the drum e^{12} of the stroke apparatus is set in rotation through 120 the medium of the gearing f^2 , e^5 , e^1 , e^2 , e^9 , e^{10} , e^{11} . Suppose the drum e^{12} rotates in the direction of the arrow y (see Fig. 3) then under the action of this rotation, the roller d^2 , which hitherto just touched the transi- 130

tion arc e^{14} of the rib e^{13} , begins at the same time to slide up the part of the rib e^{13} of larger diameter. The double-armed lever D, D^4 is thereby rocked in the direction of 5 the arrow z (see Fig. 3) and the toothed sector d^1 mounted on the end of the lever arm D^4 commences an upwardly directed movement of the rack c^1 and consequently of the piston rod C of the controlling 10 valve B.

As soon as this movement of the piston rod C has caused the movable circuit closing device c^5 to come into contact with the fixed circuit closing device b^7 , the circuit J, 15 $i^1, c^5, b^7, g^7, g^6, i^2, J$ containing the magnet winding g^6 is closed. The cut-off device G is therefore very rapidly raised out of the closed position into the open position by the now energized magnet g^5, g^6 . The distance 20 of the circuit closing device b^7 from the middle position of the circuit closing device c^5 is much less than the length of the valve sleeve of the piston c^2 so that the controlling valve B still remains closed for a certain 25 time after the opening of the cut-off device G for the passage of the water under pressure. This latter therefore passes first from the pipe b^1 into the part of the pipe b^5 in front of the cut-off device G through the 30 lower part of the opened cut-off device G, the adjoining part of the pipe b^5 , and the pipe a^6 into the cylinder A⁸. The piston a^4 consequently rises and imparts to the gun barrel A an elevating movement. The water 35 displaced by the piston a^4 flows away at the same time through the pipe a^7 and the waste water pipe a^9 opened by the cut-off device G. The ratios are so determined that the movement of the gun barrel takes place 40 at a moderate speed. During the further rocking of the double-armed lever D, D^4 the piston valve c^2 of the controlling valve B begins to admit the water under pressure from the pipe b^1 through the passage b^3 into the 45 pipe a^8 . The piston c^3 simultaneously opens the passage b^2 leading to the waste water pipe, so that the water displaced by the piston a^4 now also flows away through the waste water pipe a^7, b^2 .

50 In proportion as the passage b^3 gradually opens, so the pressure in the pipe a^8 rises, and with it the speed at which the piston a^4 rises in the cylinder A⁸ together with the front part of the gun barrel A. In consequence 55 of this rise of the front part of the gun barrel A the rear part of the gun barrel sinks with the toothed sector a^{14} . This movement of the toothed sector a^{14} results in a rotation of the drum e^{12} in the direction of the arrow y through the medium of the gearing already mentioned. The drum e^{12} is thereby returned to the position which it occupied before the beginning of the rotation, by the driving shaft f^1 and in which 60 the roller d^2 assumes the position shown in

Fig. 3 with respect to the transition sector of the rib e^{13} denoted by c^{14} . The piston rod C accordingly again approaches its middle position, the piston c^2 gradually closing the passage b^3 for the water under pressure 70 and the piston c^3 the passage loading to the waste water pipe b^2 , so that finally water under pressure can only pass to the cylinder A⁸ through the cut-off device G and then into the waste water pipe a^9 . 75

The movement of the gun barrel A has in the meantime gradually slowed down corresponding to the shutting off of the valve passage b^3 . When the piston rod C has sufficiently approached its middle position after the conclusion of the shutting off of the passage b^3 and of the waste water pipe b^2 that the contact between the circuit closing devices c^5 and b^7 is again interrupted, the magnet coil g^6 is deenergized. The cut-off 80 device G is therefore rapidly closed under the action of the spring g^4 . The ratios for the closing of the cut-off device G are so determined, that the end of the closing operation coincides with the instant in which the 85 movable circuit closing device c^5 again has reached its middle position, shown in the drawing. As at this instant all the pipes are shut off the gun barrel A remains stationary in that angular position which it 90 had attained at the end of the closing operation of the device G. This angular position corresponds exactly to the angular position of the transmitter K, because all the 95 parts of the valve gear assume the same position with respect to each other which they had occupied before the commencement of the controlling operation.

It is obvious without any further description, that the operation described must take 100 place in an exactly similar manner, when not a raising but a depression of the front part of the gun barrel A is required. For this purpose it is only necessary to rotate the transmitter shaft k^7 and consequently 105 the armature shaft f^1 of the receiver F in the reverse direction to that in which it was previously rotated. The direction of motion of the other parts concerned is also 110 reversed, and the movable circuit closing device c^5 is brought into contact with the circuit closing device b^8 instead of with the circuit closing device b^7 . The cut-off device H is accordingly brought into the open position, and the cut-off device G remains 115 closed. The water under pressure therefore passes by the route b^1, b^6, a^7 into the cylinder A⁸ and the water displaced by the piston a^4 escapes through the pipes a^6, a^8 . The piston a^4 and consequently the front part of 120 the gun barrel A therefore begin to sink. During the further course of the sinking of the piston rod C the controlling piston c^4 opens the passage b^4 , so that water under 125 pressure can now also pass through the 130

pipe a^7 above the piston a^4 . At the same time the controlling piston opens the way to the waste water pipe b^2 . The sinking of the gun barrel brings about through the medium of the toothed sector a^{14} and the stroke apparatus connected therewith the return of the controlling valve, which takes place in a manner which corresponds exactly to that in which it previously took place, but in the reverse direction.

It is obvious at once without any further description, that the gun barrel A need not be at rest when the transmitter K and with it the receiver F are adjusted.

15 Furthermore no special description is needed of the way in which the apparatus described works, if the assumption that the ship neither pitches nor rolls, be abandoned. In this case it is only necessary by suitably 20 turning the hand wheel k^3 to train the telescope k^{10} permanently on the target and thus to impart to the transmitter an additional rotation corresponding to the angle of pitch or roll.

25 A principal advantage of the apparatus which forms the subject matter of this invention is that the gun barrel can be moved into the position required by the adjustment of the transmitter with great accuracy 30 and free from shock.

The above description of the working of the apparatus shows in particular that the speed at which the gun barrel moves when the cut-off G or H is open and the controlling valve B simultaneously closed, is only 35 a moderate one, whereby the transition of the gun barrel at the beginning and the conclusion of the adjusting operation from the position of rest to this speed or from this 40 speed to the position of rest, although it takes place very rapidly, cannot result in the production of jerky movements producing individual oscillations. Furthermore the fact that the gun barrel moves with only 45 a moderate speed before the conclusion of the adjusting movement and is transferred from this condition to the condition of rest by a rapidly-closing cut-off device insures that the gun barrel comes to rest finally and 50 with certainty at a moment which corresponds exactly with the shutting off of the said cut-off device. The shutting off of the quick-acting cut-off device lies however exactly so much behind the moment of the separation of the movable circuit closing device 55 from the fixed circuit closing device in contact with it, as the movable circuit closing device requires time to pass over the route from the point of separation to the middle 60 position shown in the drawing. The gun barrel is thus brought to rest with very great accuracy the moment it has attained the angular position corresponding to the adjustment of the transmitter.

65 The transition from the moderate speed

at which the gun barrel moves when the cut-off devices are open but the controlling valve closed to the speed at which the movement of the gun barrel takes place when the cut-off device and the controlling valve are open 70 simultaneously takes place with uniform acceleration or retardation. In consequence no shocks can take place in this part of the adjusting movement, which would bring about individual oscillations or unfavorable 75 strains on the driving mechanism.

Finally in the present invention the controlling valve only exerts an accelerating or retarding action on the movement of the gun barrel, whereas rapidly closing cut-off 80 devices are the controlling factors for the beginning and above all the end of the movement of the gun barrel, and it is not necessary, to construct the controlling valve as an accurately working element. The laps 85 may therefore be so widely chosen that small variations in the position of the controlling edges or an unavoidable wearing of these edges do not prejudicially affect the accuracy of the adjustment of the gun barrel. The fact that the lap of the valves may be of large dimensions and that an accurate adjustment of the controlling valve is not necessary, permits in its turn of making the appliances which serve to return the 90 controlling valve considerably smaller than if an accurate adjustment of the controlling valve were necessary. The invention is therefore also distinguished by the specially 95 small amount of space taken up by its valve 100 gear.

Claims:

1. A long distance control apparatus for a hydraulic gun pointing mechanism which comprises, a slow acting control device, 105 quick acting valves, a hydraulic device for pointing the gun, said hydraulic device, quick acting device and slow acting controlling device being operatively connected for hydraulic transmission, a sighting device, 110 an operating gear, means operatively connecting said sighting device to said operating gear for causing the same to function, means positively connecting said operating gear to the slowly acting controlling device, 115 a contact device operatable by the slow acting controlling device, electro-magnets for actuating the quick acting device and a circuit including said electro-magnets and contact devices. 120

2. A controlling device for guns which comprises an elevating mechanism of the hydraulic type, a system of controlling valves for regulating the admission of a hydraulic medium to the hydraulic device, 125 said system of valves including a slow acting valve, a pair of quick acting valves, a sighting device and means dependent upon the position of the sighting device for controlling the position of the slow acting valve 130

and electric means operatable by the slow acting valve for operating the quick acting valves.

3. A controlling device for guns which 5 comprises a hydraulic mechanism, a system of valves for controlling the admission of the hydraulic operating fluid to the hydraulic device, said system comprising a slow acting valve, and a pair of quick acting 10 valves, a sighting means, a controlling gear operatively connected to the gun and to the slow acting valve, electrical means operatively connecting the sighting device to the controlling gear, a contact device operated 15 by the slow acting valve, electro-magnets for operating said quick acting valves and a circuit connecting said electro-magnets and contacts, said slow acting valve being so arranged that the contact device operates a 20 quick acting valve before the slow acting valve is open, substantially as and for the purpose set forth.

4. A control device for guns which com-

prises a hydraulic elevating mechanism, a valve system controlling the hydraulic fluid, 25 said system including a slow acting valve and a pair of quick acting valves, said quick acting valves being connected in parallel hydraulically with said slow acting valve, each of said quick acting valves being adapted to simultaneously control an inlet and outlet pipe connected to the hydraulic mechanism, a controlling gear for operating the slow moving valve, a sighting device and electric means operatively connecting said 30 sighting device to the controlling gear and electrical means operatable by the slow moving valve for operating the quick moving valves.

The foregoing specification signed at Es- 40 sen, Germany, this 16th day of June, 1920.

DR. WALTHER AKEMANN.
